UNITED STATES PATENT OFFICE.

DAVID N. HYRE, OF RICH HILL, MISSOURI, ASSIGNOR TO HARRISON L. HYRE, OF LEXINGTON, ILLINOIS.

WEATHER-STRIP.

SPECIFICATION forming part of Letters Patent No. 340,047, dated April 13, 1886.

Application filed August 18, 1885. Serial No. 174,732. (No model.)

To all whom it may concern:

Be it known that I, DAVID N. HYRE, a citizen of the United States, and a resident of Rich Hill, in the county of Bates and State of Missouri, have invented certain new and useful Improvements in Weather-Strips; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of the lower portion of a door provided with my improved weather-strip, showing the door opened. Fig. 2 is a vertical section through the closed door and its sill. Fig. 3 is a plan view of the sill and the wire bracket, and Fig. 4 is a perspective detail view of the wire bracket detached.

Similar letters of reference indicate corresponding parts in all the figures.

My invention has relation to weather-strips for doors, which consist in a strip of metal hinged or pivoted at its upper edge to the outer side of the door near its lower edge, and contemplates more particularly an improvement upon the weather-strip for which Letters Patent were granted to Harrison L. Hyre on the 27th day of May, 1879, No. 215,750; and it consists in the improved construction and combination of parts of a wire bracket which will support the lower edge of the hinged weather-strip above the floor when the door is opened, as hereinafter more fully described and claimed.

In the accompanying drawings, the letter A indicates the door-frame. B is the sill, and C is the door. D is the metallic weather-strip, which is hinged at its upper edge to the front side of the door, under the strip E, which fits over the edge of the weather strip in the same manner as already described in the specification, and shown in the drawings of the patent above referred to, and all of which parts consequently will need no further explanation.

I have shown the metallic weather-strip hinged in the above-described manner, for the reason that I prefer to use my bracket with

the said construction of a strip; but it will be readily understood that the strip may be hinged in any other suitable manner, or may slide vertically, the bracket being applicable to any strip capable of displacement in an upward or outward direction.

The bracket F consists of a curved or nearly segmental portion, G, the outer end of which is bent downward, as shown at H, and driven into the door-sill a short distance from the hinge-jamb of the frame, and the inner end, I, of the curved portion G is bent inward parallel with the line of the sill, and again bent back parallel with the sill and the other portion, whereupon it is bent upward at a right angle, forming an upright portion, J, and at last bent toward the door-jamb at a right angle to the former portion, forming a portion, K, which is driven into the door-jamb.

The entire bracket is formed by one piece of wire or thin metallic rod, and the ends are preferably sharpened, so that they may be driven into the sill and jamb of the door in the same manner as a common nail.

The bracket projects inward and is in a plane with the upper side of the door-sill, and the sill has preferably a groove, L, into which the outer portion of the curved part of the wire may rest, bringing its upper side flush with the upper face of the sill, and the jamb is grooved at M in a similar manner, for the reception of the upright portion of the inner end of the wire.

It will be seen that this bracket will not only serve to raise the lower edge of the weather-strip, but will also support the lower edge of the door, preventing it from dragging and binding against the floor, and it will be a sufficient distance above the floor to admit of the edge of a carpet being inserted under it, and will be sufficiently open to allow the portion of the carpet below it to be swept and kept clean, preventing any accumulation of dirt, or breeding of moth or other vermin.

It will be seen that by constructing my improved wire bracket of the form shown and described the lower edge of the weather-strip and the lower edge of the door will, when the door is opened at any angle, be supported on

three portions of the single-wire bracket, owing to the peculiar form or curvature of the same, the wire bracket thus forming a far more effective support than if it were merely curved in a semicircular form, so that the weather-strip and the lower edge of the door would come in contact with one portion of the wire only, as has heretofore been the case. The peculiar advantages of this construction will be readily understood by reference to Fig. 1 of the drawings.

The bracket is simple of manufacture, and is simple of application, and may be used with any weather-strip capable of displacement in an upward direction, doing away with the necessity of having spring attachments, knobs, or handles, or other means for raising and holding the strip when opening or closing the door.

I am aware that brackets composed of a single curved wire or thin metallic rod have been secured at the hinge edge of a door frame for the purpose of raising the lower edge of the weather-strip or for the purpose of supporting the lower edge of the door; and I do not, therefore, claim such construction, broadly; but

What I claim as my invention, and desire to secure by Letters Patent of the United States, 30 is—

1. A bracket for raising the lower edge of a weather-strip, consisting of a rod bent to form a curved portion, having its outer end bent downward and pointed, having its inner portion bent inward and doubled parallel to itself, bent upward at a right angle, and bent outward from the curve and pointed, as and for the purpose shown and set forth. 35

2. In combination with a door having a weather-strip capable of upward displacement, 40 a bracket consisting of a rod formed with a curved horizontal portion, a downwardly-bent pointed portion at one end of the curved portion driven into the sill of the door, an inwardly-bent portion doubled back parallel with itself, and an upwardly-bent portion at the end of the doubled portion, having its end bent at a right angle to it and pointed and driven into the jamb of the door at the hinge edge of the door, as and for the purpose shown 45 and set forth.

In testimony that I claim the foregoing as my own I have hereunto affixed my signature in presence of two witnesses.

DAVID N. HYRE.
